UNITED STATES PATENT OFFICE.

JOHN TYLER HICKS, OF SOMERVILLE, MASSACHUSETTS, ASSIGNOR TO THE
HOTEL SECURITY CHECKING COMPANY, OF PORTLAND, MAINE.

METHOD OF AND MEANS FOR CASH-REGISTERING AND ACCOUNT-CHECKING.

SPECIFICATION forming part of Letters Patent No. 500,071, dated June 20, 1893.

Application filed July 21, 1890. Serial No. 359,462. (No model.)

To all whom it may concern:

Be it known that I, JOHN TYLER HICKS, a citizen of the United States, residing at Somerville, in the county of Middlesex and State of Massachusetts, have invented certain new and useful Improvements in the Art of Cash-Registering and Account-Checking; and I declare that the following is a full, clear, and exact description of the invention, which will enable others skilled in the art to which it appertains to make and use the same.

Heretofore it has been and it now is extremely important for restaurant and hotel keepers to be able to ascertain accurately whether or not the different articles delivered to the different waiters by the kitchen, bar, cigar stand and other departments are all properly accounted for and paid for to the cashier, and whether or not the cashier makes proper return of the moneys paid to him by the customers. Waiters favor customers by giving them smaller checks or charging them smaller amounts than they should, either in the hope of a gratuity from the customer or sharing the discount in direct collusion with him, and sometimes, when it is feasible, either carelessly or intentionally permit customers to leave without paying anything whatever. The cashier also reports less cash than he has received. And when there is no dishonesty, the negligence of waiters and of cashiers, which cannot be discovered and therefore cannot be controlled, has in like manner caused heavy losses to their employers. This evil is so great that many elaborate systems have been devised to overcome it, but have thus far met with imperfect success. Intricate and costly machines have been introduced, which, though expensive and difficult to successfully operate, have sold largely, because of the widespread appreciation of the absolute necessity of some means, which shall enable the hotel and restaurant proprietor to detect the carelessness or dishonesty of particular individuals in his employ.

The object of my invention is to accurately check the account of each individual waiter and of the cashier.

To carry my invention into effect I provide each waiter with slips of paper bearing some mark which shall distinguish the slips from

those used by any other waiter in the same establishment, and I provide the person in charge of each department, which fills an order given by waiters, with a sheet or sheets of paper also so marked that a particular sheet or column shall be appropriated to each of said waiters and to him only. These marks may be the name of the waiter, or a number, or the color of the paper, or any arbitrary symbol, though, in practice, I have given a number to each waiter, and required him to wear a badge showing it, and provided one sheet for each department to be ruled lengthwise into parallel columns, each headed with a corresponding number, and believe this to be the easiest and simplest way of connecting the waiter, the slip used by the same waiter, and the sheet or column appropriated to him by each department.

Figure 1^a of the drawings represents such a sheet as is used by the different departments, which is marked A, and Fig. 1^b such a slip as is used by the waiters, which is marked a. In Fig. 1^b the slip a is marked "waiter No. 1" indicating that it is used by the waiter designated by that number, and in Fig. 1^a, the sheet A is prepared for an establishment having six waiters. When a customer gives an order, if for instance, for food, the waiter, who receives it, goes to the kitchen and repeats the order, passing one of his said slips, either at that time or when the order is filled, to the chief of that department. When the order is filled, the plate or tray containing it passes in sight of said chief, who notes what is on the plate or tray and enters the selling price of the same, in duplicate, on said slip, and on the sheet or column appropriated to the waiter, and returns the slip to the latter. The slip is then taken by the waiter to the customer with the order. Each item of the order may be entered separately on the slip and on the sheet if so desired, but, in practice, I have found it more convenient and usually sufficient for the purposes of my invention to enter the whole of any one order as a total. If any subsequent order is given by the same customer, the same process is repeated, to whatever department the order goes, and the price of the order is entered upon the same slip and is also charged to the same waiter.

on the sheet or column appropriated to him by the department which fills the order. When the customer has bought all he wishes he pays the sum of all the charges on the slip to the cashier, who takes the slip from him and retains it till the end of the day. Subsequent orders received by the same waiter from other customers are entered for each customer on a separate slip belonging to said waiter, but are entered by each department in the same column or on the same sheet appropriated to said waiter, as already explained. At the close of business, or whenever desired, the sum of the slips of each waiter in the hands of the cashier can easily be compared with the sum of the items charged to him by the departments collectively, and the amount charged to all the waiters with the sum of all the items of all these slips in the hands of the cashier and with the cash reported by the latter. If there has been no negligence or dishonesty the accounts will agree; and if there has been any, so that the accounts do not agree, it is perfectly easy to ascertain the person who is at fault.

Figs. 2^a and 2^b represent two slips, marked b and c respectively and used by the same waiter No. 6.

Figs. 2^c, 2^d and 2^e represent three sheets for three departments, namely, D used by the kitchen, E used by the wine room or bar, and F used by the cigar stand. In the example represented by these sheets and slips and the entries upon them, a customer is supposed to make two successive, but separate, calls for articles furnished by the kitchen and sold for twenty, and seventy-five cents severally, and next to order from the wine room or bar, articles costing thirty cents, and to end with an order for a cigar at fifteen cents. These respective sums are severally marked by the heads of the several departments in the column No. 6 on the several sheets, and are also simultaneously stamped in duplicate upon slip b, Fig. 2^a, when each order is delivered to the waiter. Another customer then enters and is served from the bar, kitchen and cigar stand, in the order just named, and simultaneous entries of the value of the articles delivered to the waiter for him are also in like manner marked in duplicate upon the slip c, Fig. 2^b and in column No. 6 of the proper sheet. The slips b and c, and the sheets D, E and F show the appearance of the slips when paid and in the hands of the cashier, and of the sheets of the three departments at the end of the day so far as the sales to the two supposed customers are concerned.

Figs. 3^a, 3^b and 3^c, show three sale slips of waiter No. 3 marked respectively d, e and f.

Figs. 3^d, 3^e, 3^f, 3^g show four sale slips of waiter No. 5, marked respectively g, h, i, j.

Figs. 3^h, 3ⁱ and 3^k, show three sheets used by the kitchen, wine room or bar, and cigar stand, marked respectively, G, II and I. These several sheets are all marked respectively with the selling prices of articles sup-

posed to be sold by waiters No. 3 and 5, to successive customers, as will be seen by inspection. Should the first customer of a waiter not have finished his order from any particular department before a second customer of that waiter begins to order from the same department as for instance, if Mr. A orders from the kitchen an article worth fifteen cents, then Mr. B orders from the same department something costing fifty cents, and Mr. A afterward further orders from the kitchen something worth seventy-five cents, it is evident that while upon the slip given to Mr. A and paid by him to the cashier, the two orders of Mr. A will follow each other directly, the column appropriated to this waiter on the sheet of the kitchen department will show the order of Mr. B stamped between the two orders of Mr. A because each order is charged to the waiter in his column at the moment of its delivery to him.

This invention accomplishes, in practice among others, the following results, some of which are accomplished by some of the machines and systems now in use, but all of which, it is believed, have never been accomplished by any machine or system prior to this invention.

First. It enables the proprietor to readily ascertain whether the cash received by him corresponds with the aggregate prices of all the articles sold by him during any given period.

Second. It enables the proprietor to ascertain the accuracy, care, and honesty of each waiter separately, and of the cashier.

Third. It enables the proprietor to ascertain just what each waiter has done, what he has sold, and how many customers he has served, and thus to judge of his efficiency, energy, and value to his employer.

Fourth. If a customer leaves without paying his bill, it enables the proprietor to ascertain which waiter is at fault.

Fifth. It distinguishes the receipts of the different departments, as separate sheets are kept in each, and enables the proprietor to ascertain what is sold by each department, as, for example, by the cigar stand, the bar, or the kitchen. This may be further aided by the use of different colored inks in the different departments, if desired.

Sixth. It promotes a saving in salaries and expenses of business, as each waiter, being aware that his comparative efficiency will be known by his employer, even if the latter is absent from the room, will naturally try to do as much work as possible, so as to show a good average and retain his position.

Seventh. It protects the customer. As each order is charged separately, and at the close of a meal the price of each order, though not its nature, is seen to have been separately entered upon the slip, instead of a single check for the whole meal being given to the customer, the latter is enabled the more readily to detect any possible error and have it

rectified. He is also more quickly served by the waiter, whose interest has now become to serve him speedily, and less likely to be annoyed by his waiters loitering for tips instead of attending to other customers.

8 Eighth. In some hotels and restaurants the employés are allowed to eat from the bill of fare at will, without payment. With this system in use, requiring that everything shall be charged to the waiter, whether served to a customer, an employé, or the proprietor himself, and the further requirement that each person permitted to eat without paying shall sign his name on the slip on which the value of the article consumed by him is entered in order that the same may be deducted from the amount for which the waiter is to be held liable, the proprietor will be enabled to see if the privilege is being abused and by whom and to what extent.

9 Ninth. Saving in expense over other cash registering or account checking systems in use and the combination in one system of the accurate registration of cash received with the accurate checking of accounts.

10 Tenth. If the system is properly used, it enables the landlord or restaurant keeper to ascertain if all the slips have been paid by the customers of any waiter, by simply counting the number of charges made against such waiter in all the departments, and the number of items on such waiter's slips in the hands of the cashier. If they agree in number, it shows that all the slips have been paid. 15 If it is then desired to ascertain the amount of the sales made by such waiter, this can be done by simply adding up his accounts with the different departments, without adding up the amount shown by the slips. These will 20 prove trial balances of the business of such waiter, and if extended to the business of all the waiters will serve as trial balances of the whole business of the establishment, and can be taken by any person who understands 25 figures, even if wholly ignorant of bookkeeping. This, in many cases, will enable the proprietor to avoid the expense of a trained bookkeeper.

It is evident that this system can be applied

not only to restaurants, but also to all places 50 where goods are sold, and whether there is one department only, or more, and that the dishonesty or carelessness of any employé cannot fail to be detected unless the clerk or waiter, the head of department, and the customer are all in collusion,—which will not often occur.

Having fully described my invention, what I claim, and desire to secure by Letters-Patent, is—

1. The herein-described improved means for securing hotel or restaurant proprietors or others from losses by the peculations of waiters, cashiers or other employés, which consists of a sheet provided with separate spaces, 65 having suitable headings, substantially as described, said headings being designatory of the several waiters to whom the several spaces on the sheet are individually appropriated, in conjunction with separate slips, each so 70 marked as to indicate the waiter using it, whereby the selling price of all the articles sold may be entered in duplicate, once upon the slip of the waiter making the sale, and once upon his allotted space upon the main 75 sheet, substantially as and for the purpose specified.

2. The herein-described improvement in the art of securing hotel or restaurant proprietors and others from losses by the peculations of 80 waiters, cashiers or other employés, which consists in providing separate slips for the waiters, each so marked as to indicate the waiter using it, and in entering upon the slip belonging to each waiter the amount of each 85 sale that he makes, and also in providing a main sheet having separate spaces for the different waiters and suitably marked to correspond with the numbers of the waiters and of their slips, and in entering upon said main 90 sheet all the amounts marked upon the waiters' slips so that there may thus be a duplication of the entries, substantially in the manner and for the purpose specified.
